US00D569373S

(12) **United States Design Patent** (10) **Patent No.:** **US D569,373 S**
(45) **Date of Patent:** **** May 20, 2008**

(54) **PORTABLE PERSONAL COMPUTER**

(75) Inventors: **Se-O Lee**, Seoul (KR); **Joung-Shin Seo**, Seoul (KR); **Jin Kwon**, Seoul (KR)

(73) Assignee: **Samsung Electronics Co., Ltd.**, Suwon, Kyunggi-Do (KR)

(**) Term: **14 Years**

(21) Appl. No.: **29/262,197**

(22) Filed: **Jun. 28, 2006**

(51) **LOC (8) Cl.** **14-02**

(52) **U.S. Cl.** **D14/341**

(58) **Field of Classification Search** D14/341, D14/342, 343, 344, 345, 346, 347, 452, 374, D14/426, 496, 137, 138, 247, 248, 455, 456, D14/420, 427, 432, 439, 440, 441, 448, 125, D14/129, 130, 250, 389, 147, 218, 156, 126; D21/517, 329, 331, 686; D18/7, 6; D10/65, D10/104; 345/169, 173; 379/433.04, 433.06, 379/433.07, 433.11, 433.12, 433.13; 348/14.02; 455/556.1, 556.2, 566, 575.1, 575.4, 90.3, 455/575.3; 349/12; D13/168; D6/596, D6/601, 605; 361/814; 341/22

(57) **CLAIM**

The ornamental design for a portable personal computer, as shown and described.

DESCRIPTION

FIG. 1 is a top front perspective view of a portable personal computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
